UNITED STATES PATENT OFFICE

1,980,802

FUEL GAS GENERATOR

Adolph Jagmin, Cicero, Ill.

Application September 29, 1932, Serial No. 635,431

1 Claim. (Cl. 261—21)

This invention relates to improvements in fuel generators and pertains particularly to an improved fuel gas generator.

The primary object of the present invention is to provide a new and novel apparatus for effecting the automatic generation or manufacture of a gas suitable for all fuel purposes, from air and a volatile liquid fuel, such for example as gasoline.

10 Another object of the invention is to provide a novel form of apparatus for mixing air with a volatile liquid fuel so as to form a fuel gas having a high content of thermal units which is ready for use in a burner or in any other apparatus 15 without further mixture of air therewith.

Still another object of the invention is to provide a fuel gas generator having a novel assembly of control valves for pipe lines through which air and a volatile liquid fuel is passed under high 20 pressure and for controlling a pipe line common to the first mentioned lines into which the latter discharge, whereby a completely carbureted mixture of the air and liquid fuel is obtained so that the mixture is ready for use without further treatment.

25 A still further object of the invention is to provide in an apparatus of the character herein described a novel pump mechanism by which the desired air pressure for the system is developed.

30 The invention will be best understood from a consideration of the following detailed description taken in connection with the accompanying drawings forming part of this specification, with the understanding, however, that the invention 35 is not confined to any strict conformity with the showing of the drawings but may be changed or modified so long as such changes or modifications mark no material departure from the salient features of the invention as expressed in the appended claim.

In the drawings:—

Figure 1 shows the fuel gas manufacturing apparatus embodying the present invention, parts thereof being broken away;

45 Figure 2 is a vertical sectional view taken substantially upon the line 2—2 of Figure 3;

Figure 3 is a sectional view taken upon the line 3—3 of Figure 1 and showing a portion of the pump cross-head guide in section;

50 Figure 4 is a sectional view taken upon the line 4—4 of Figure 3;

Figure 5 is a detail vertical section through the pump piston structure;

Figure 6 is a sectional view taken on the line 55 6—6 of Figure 5;

Figure 7 is a detail view in vertical section of a separating tank of the apparatus showing adjacent connections in elevation;

Figure 8 is a detail view upon an enlarged scale of a valve and position indicating means therefor together with a sectional view of an adjacent fine adjustment or needle valve;

Figure 9 is a view in elevation of a fine adjustment valve;

Figure 10 is a sectional view taken substantially upon the line 10—10 of Figure 1;

Figure 11 is a detail sectional view of a mixing chamber through which the prepared fuel gas is passed prior to being used.

Referring now more particularly to the drawings wherein like numerals of reference indicate corresponding parts throughout the several views, the numeral 1 indicates generally the pumping unit for the present fuel generating system, which is employed for developing the required air pressure therein.

This pump unit consists of a vertically disposed pump cylinder 2 the lower end of which is mounted in a base 3 which has a lateral outlet 4 with which is connected a short pipe line 5 having 80 interposed therein the outwardly opening check valve 6. This pump unit is mounted upon a suitable support such as the platform 7 and leading downwardly from the base 3 is a pipe line 8 in which is a hand operated valve 9. This pipe 85 line 8 is provided for the purpose of draining oil from the pump cylinder after it settles in the lower or base part thereof.

The upper end of the cylinder 2 is closed by the head 10 through which extends a piston rod 90 11. A suitable stuffing box 12 closes the passage about this rod.

Within the cylinder 2 is a piston 13 which is provided at its upper and lower ends respectively with the open chambers 14 and 15 and the portion of the piston body between these chambers has a plurality of air passages 16 therethrough arranged concentrically about a central valve stem passage 17.

The inner edge of the chamber 14 is cut away 100 to form a valve seat 18 against which positions a disk valve 19. This valve 19 has a stem 20 which passes downwardly through the passage 17 and surrounding its lower end is a coil spring 21 which has one end within the chamber 15 and 105 bearing against the piston while its other end is held by the nuts 22 which are threaded upon the stem.

The upper corner or edge of the piston body is beveled off or cut away as indicated at 23 and 110

this bevel provides with the adjacent cylinder wall a pocket about the upper end of the piston in which oil may be placed.

As shown the lower end of the piston rod 11 is threaded into the top of the valve 19. From this it will be apparent that as the piston is driven downwardly the valve 19 will be held against its seat 18 and the desired pressure will be generated to force air from the cylinder into the pipe 5 past the check valve 6. Upon the up-stroke of the piston the valve 19 will be lifted from its seat and air which enters the cylinder through the apertures 24 in the top thereof, will pass downwardly past the piston to the under side thereof.

Mounted upon the platform 7 adjacent the cylinder are the two spaced parallel guides 25 which have their opposed faces provided with grooves 26. These guides are vertically arranged 20 and are connected at their upper and lower ends by the members 27 and 28 respectively.

Disposed between the guides 25 is a cross head 29 which has the lateral ears 30 each of which slidably position in a groove 26. At one side this 25 cross head has the extension 31 through which the upper end of the piston rod 11 passes and to which it is secured by the nuts 32. Adjacent its opposite side the cross head 29 has the depending ear 33 with which is pivotally connected one end 30 of a link 34.

The structure 7 has mounted thereon a power unit such as the electric motor 35, and adjacent this unit is mounted in suitable bearings a shaft 36 which carries a gear 37.

35. The gear 37 meshes with a driving pinion 38 carried by the armature shaft of the motor and upon the outer end of the shaft 36 from the gear 37 is secured a crank arm 39 which is provided with the longitudinal slot 40. The other 40 end of the link 34 is connected with the crank 39 by the bolt 41 which is adjustably secured in the slot 40 and constitutes a means for varying the throw of the crank and the extent of travel of the piston.

45. The pipe 5 connects with a pipe line 42 at the coupling 43 and below this coupling is a pipe 44 which has a hand operated valve 45 therein, this pipe being threaded so that in the event that the compressor unit which is connected with the coupling 43 becomes inoperative another unit 50 of a similar character may be hooked up with the pipe 42 for the continuance of the operation of the apparatus.

Above the coupling 43 the pipe 42 discharges 55 into the lower part of a separating tank 46 and between this tank and the coupling is a hand valve 47 and a valved faucet 48 which leads off from the side of the pipe.

At the top of the tank 46 is a four-way coupling 60 49 to one arm of which is connected a perforated pipe 50 which extends downwardly into the tank 46 and terminates short of the bottom thereof. The horizontal or lateral arms of the coupling 49 have connected therewith pipes 51 and 52 and the 65 upwardly directed arm of the coupling is connected with a pressure gauge 53. The pipe 51 connects with a high pressure air tank 54 and has therein a hand valve 55.

The pipe 52 leads to and enters the lower end 70 of a tank 56. This tank contains the volatile liquid fuel with which the air compressed by the pump unit 1 is mixed. The air passing through the pipe 52 is discharged into the liquid and bubbles up therethrough into the top of the tank, the tank being normally kept approximately half

full of the liquid fuel. A hand valve 57 is inserted in the pipe line 52 for the purpose of cutting off this line as necessary, as will be hereinafter described.

The top of the tank 56 has connected therewith the short vertical pipe 58 in which is a valve 59 and which terminates at its upper end in a cup or filling receptacle 60. There also enters the tank 56 through the top one end of a pipe line 61 which turns back and is directed downwardly to join by means of the three-way coupling 62, a pipe line 63 which leads to a storage tank 64. The third arm of this coupling 62 has connected therewith one end of a pipe line 65 which at its other end enters the tank 56 adjacent the bottom thereof.

As shown the tank 64 is placed at a higher elevation than the tank 56 and the bottom of the tank 64 is connected with the bottom of the tank 56 by the pipe line 66 in which is a hand operated valve 67. This pipe 66 provides a means whereby any condensate from the fuel gas in the storage tank 64 may be returned to the tank 56 when certain of the valves are closed as will be hereinafter more fully described. The tank 56 is also provided with a valved drain or clean-out pipe 68 in its bottom, as shown.

The numeral 69 designates a fuel consumer, such for example as a stove, which is provided with a plurality of burners 70. Each of these burners is in communication by means of a lead-in pipe 71 with a manifold 72 which is provided with a plurality of needle valves 73. These lead-in pipes 71 may be the pipes commonly employed in gas stoves with their outer ends altered by forming the tapered passage 74 to receive a plug 75 which is provided with a tapered bore in which the point of the needle 76 positions. The plugs 75 are detachably mounted in their respective valves 73 as shown, so that they may be readily replaced as desired.

One end of the manifold 72 has connected therewith an end of a pipe line 77 in which is a hand operated valve 78 and the other end of this line passes into the tank 64 through the top 79 thereof. The other end of the manifold 72 is connected with a pipe 79 in which is a valve 80. This pipe provides a means for draining any fluids which may have settled in the manifold.

Each of the pipes 61 and 65 has therein a rotary plug valve or any other suitable type of heavy duty valve, the valve and pipe 61 being indicated by the numeral 81 while the one in pipe 65 is indicated by the numeral 82. These valves 81 and 82 are controlled by the elongated arms 83 and 84 which in addition to providing a means for actuating the valve serve as an indicator of the degree to which the valve is opened.

Mounted upon each pipe concentric with the valves 81 and 82 is a graduated segment 85 over which the free end of the adjacent valve arm 86 positions, as shown.

Adjacent each of the valves 81 and 82 are the fine adjustment or needle valves 86 and 87 and these valves are interposed between the valves 81 and 82 and the coupling 62 with which the pipes 61 and 65 connect.

As shown in Figure 8 these valves consist of a body 88 through which a small bore 89 is formed and a needle 90 threads into the body 88 so that its point enters the bore 89 and by making a suitable adjustment of this needle a fine adjustment of the amount of fluid passing through the valve may be had. After the necessary adjustment 150

of the needle is made a lock nut 91 which is threaded on the needle, is threaded down against the body of the valve so as to hold the needle against accidental movement. For the purpose of illustration the valve 87 is shown in section in Figure 8 with the adjacent valve 82 and the parts associated therewith.

The pipe 63 also has therein a rotary valve 92 similar to the valves 81 and 82, and a needle valve 93 similar to the valves 86 and 87. This valve 92 has an arm 94 which coacts with the graduated segment 95 to indicate the degree to which the valve is opened. The fine adjustment valve 93 is located in the pipe 63 between the heavy duty valve 92 and the tank 64.

In addition to having a pressure gauge 96, the tank 56 has connected therewith, through a portion of the pipe 61, a pipe 97 which leads upwardly to a suitable receptacle 98 located in the roof of the building in which the apparatus is set up.

The tank 98 has two outlet pipes 99 which lead therefrom through the adjacent roof, a portion of which is indicated by the numeral 99'. In the pipe 97 is a hand operated valve 100 which is normally kept closed.

At the entrance to the manifold 72 a chambered coupling 101 is located which is filled with steel wool 102 as shown in Figure 11. This acts to thoroughly mix or remix the air and vapor of the fuel gas before it enters the manifold to pass to the burners.

In the operation of the present gas generating apparatus the valves 45, 55, 67, 68, 80 and 100 are kept closed. The tank 56 is charged with a suitable amount of liquid fuel, approximately half the capacity of the tank, through the receptacle 60 and pipe 58. The valve 59 in this pipe is then closed and the pump unit 1 is placed in operation.

The air pumped through the pipe 5 passes the tank 46 and from there through the pipe 52 into the tank 56. Prior to the starting of the pump the valves 81 and 82 may be kept closed until a suitable pressure is indicated upon the indicator 96. These valves 81 and 82 are then opened the necessary distance after the necessary fine adjustment has been made of each of the valves 86 and 87 and the same adjustment is made for the valves 92 and 93. By establishing and maintaining a high pressure of air in the tank 56 the valves 81 and 82 may be adjusted so that some of the liquid will be forced up into the coupling 62 to mix with the gas laden air which passes through the valve 81. By proportioning the several valves 81, 82 and 92 and the needle valves 86, 87 and 93, in the proper manner, there will be discharged into the storage tank 64 a highly combustible fuel gas which may be drawn off and used directly at the burners 70 without the admixture of further air therewith.

While the vapor within the tank 64 will remain in suitable condition for burning in order to insure the complete or thorough mixing of the elements thereof the steel wool containing coupling 101 is provided through which the gas must pass before entering the burners.

As previously stated the connection 44 is provided so that another compressor unit may be coupled in the system in the event that the first unit breaks down.

By the provision of the tank 46 it is assured that no oil or moisture which may enter the pump will pass into the pipe 42 as any liquids which may be pumped into the tank will settle in the bottom thereof while the air rises and passes out through the perforated pipe 50.

In order to drain the tank 46 of any liquids which may collect therein the valves 47 and 57 are closed and the valve 55 is then opened together with the valve 48 and the air under pressure will pass from the tank 54 through the tank 46 and out of the faucet 48 and clear the tank.

By maintaining a high pressure of air in the tank 54 the operation of the pumping unit may be discontinued at intervals and the air from this tank used for the system as will be readily understood.

The pipe 66 is provided for returning to the main or charging tank 56 any condensate which may collect in the bottom of the storage tank. The return of the condensate is effected by opening the valves 67 and 100 so as to relieve the pressure in the tank 56 and thus permit the condensate to return by gravity thereto.

When the system is charged with the liquid fuel the valve 100 is opened so that the air within the tank 56 will be permitted to escape as the liquid is poured in through the pipe 58. By providing the tank 98 at the upper end of the pipe line 97 any liquid which may be forced up through this pipe will be prevented from escaping from the system and may flow back into the tank 56 for use.

Means is provided also for draining the manifold 72 as necessary by the provision of the pipe and valve 79-80. This valve 80 is, of course, kept closed at all times during the operation of the system.

As previously stated, the valve 9 provides a means for draining oil from the compressor and the valve 68 is also provided for the tank 56 so that any sediment may be drained therefrom, if necessary.

Having thus described the invention, what is claimed is:—

In a fuel generating system, a fuel liquid containing tank, means for injecting air under pressure into the tank below the liquid level thereof, a pipe having one end connected with the top of said tank and having its other end connected with the bottom of the tank whereby both air and liquid may be led off therefrom, a pair of valves in said pipe each comprising a body having a restricted passage therethrough and a needle disposed across the passage for controlling the flow of fluid therethrough, said valve passages being in spaced aligned relation whereby the fluids passing therethrough will oppose one another and be intimately mixed, a pipe leading off from said first pipe from a point intermediate said valves, a storage tank into the upper part of which said last pipe leads, a pair of rough adjustment valves in said first pipe disposed with said first valves therebetween, a rough adjustment valve in the second mentioned pipe, a fine adjustment valve in the second mentioned pipe between the rough adjustment valve and the storage tank, and means for conducting fuel gas from the storage tank to a point of consumption.

ADOLPH JAGMIN. 145
